WASHING MACHINE

John T. Hume, Chicago, Ill., assignor to Electric Household Utilities Corporation, Chicago, Ill., a corporation of Illinois

Application July 30, 1932, Serial No. 626,677

6 Claims. (CL 259—101)

This invention relates to improvements in washing machines and its purpose is to provide an improved machine of the type in which an oscillatory clothes agitator is located in a tub or vessel adapted to contain the clothes and the washing fluid. The principal object of the invention is to provide an improved washing machine comprising a tub for containing clothes and the washing fluid and having an improved 5 clothes agitator adapted to effect a violent, irregular and continuous movement of the clothes and washing fluid during the operation of the machine. A further object of the invention is to provide a washing machine of the type referred 10 to having an improved form of clothes agitator having a radiating plate or disk provided on the upper and lower sides thereof with irregular vanes or projections adapted to effect a turbulent and irregular agitation of the fluid throughout the 15 body thereof when in operation. Still another object of the invention is to provide a washing machine of the tub type having a clothes agitator shaft projecting upwardly from the bottom thereof and having a clothes agitator mounted on this 20 shaft and provided with a substantially horizontal disk located substantially midway between the top and bottom of the tub and provided on the upper and lower sides thereof with means for effecting an irregular agitation of the washing 25 fluid in the upper and lower parts of the tub and around the outer edge thereof. Other objects of the invention relate to various features of construction and arrangement which will appear more fully hereinafter.

30 The nature of the invention will be understood from the following specification taken with the accompanying drawings, in which one embodiment is illustrated. In the drawings,

35 Fig. 1 shows a vertical axial section through a washing machine embodying the features of the present invention;

Fig. 2 shows a horizontal section taken on the line 2—2 of Fig. 1;

40 Fig. 3 shows a top plan view of the improved clothes agitator of the present invention;

Fig. 4 is a detail section taken on the line 4—4 of Fig. 3;

45 Fig. 5 shows a side elevation of the improved clothes agitator with a portion of the upper part thereof broken away;

Fig. 6 is a detail section taken on the line 6—6 of Fig. 3;

50 Fig. 7 shows an enlarged vertical section taken 55 on the line 7—7 of Fig. 2;

Fig. 8 shows a transverse vertical section taken on the line 8—8 of Fig. 7;

Fig. 9 is a horizontal section taken on the line 9—9 of Fig. 7, showing a plan view of the operating mechanism contained within the housing; 5

Fig. 10 is a horizontal section taken on the line 10—10 of Fig. 7; and

Fig. 11 is a vertical section taken on the line 11—11 of Fig. 10.

As illustrated in the drawings, the invention 10 is embodied in a washing machine comprising a frame or housing 15 having radiating arms 15^a which are engaged on their outer vertical ends by the annular metal skirt 16. The frame 15 and skirt 16 are supported by four legs 17 which have 15 their upper ends formed as brackets 17^a to seat against the outer surface of the skirt 16. These legs on the skirt 16 are secured to the arms 15^a of the frame 15 by studs 18. The lower ends of the legs 17 are supported upon casters 19 adapted 20 to rest upon the floor or other support so that the machine may be conveniently wheeled about. The skirt 16 terminates at its upper end in a portion 16^a of restricted diameter having a rubber ring 16^b mounted upon the upper end thereof and 25 this portion of the skirt is adapted to support the tub or vessel 20 in which the clothes and washing fluid are placed during the washing operation. This tub is of cylindrical form having a bottom wall 20^a and a cylindrical outer wall 20^b which 30 fits within the upper restricted portion 16^a of the skirt 16 and is provided with an annular corrugation 20^c which overlaps and rests upon the rubber ring 16^b. In this way, the tub 20 is detachably supported upon the frame structure which 35 is carried by the legs 17. The cylindrical wall 20^b of the tub is provided adjacent its upper end with another annular corrugation 20^d and the upper edge thereof has a rubber ring 20^e fixed thereon 40 for engagement by the annular flange 21^a of the sheet metal cover 21. The flange 21^a is formed by doubling the metal at the margin of the cover and providing a downwardly and inwardly inclined flange 21^b which engages the inner curved 45 surface of the rubber ring 20^e. The cover 21 is provided at its center with a handle 21^c by which it may be conveniently removed and replaced.

The bottom wall 20^a of the tub is provided at its center with an aperture through which passes a stationary sleeve or hollow standard 22 having 50 the lower end thereof secured in a hub 23 which is formed as a part of the frame 15. The outer surface of the standard 22 is engaged within the aperture in the bottom wall of the tub by an externally threaded sleeve 24 having an outwardly 55

extending flange 24^a which underlies the bottom wall of the tub. A packing ring 25 is seated on the flange 24^a to engage the bottom wall of the tub around the aperture therein. Another packing ring or gasket 26 is seated upon the upper surface of the bottom wall around this aperture and these two packing rings are compressed to form a fluid-tight joint by a collar or nut 27 which threadedly engages the upper threaded extremity 10 of the sleeve 24 which has a fluid-tight engagement with the external surface of the standard 22. This standard 22 extends upwardly to a point above the horizontal center line of the tub and is provided at its upper end with an internal bushing 29 in which is journaled a shaft 30 adapted to be oscillated by the mechanism hereinafter described for the purpose of imparting a corresponding oscillatory motion to a clothes agitator 31 which is secured to the upper end 15 thereof and which surrounds the upper portion 20 of the standard 22.

The connection between the shaft 30 and the clothes agitator 31 is made through a block 32 which is pinned or otherwise secured upon the upper end of the shaft and which is provided around its periphery with longitudinal teeth adapted to fit between corresponding teeth formed on, and thus to form a splined engagement with, the hub 31^a of the clothes agitator. The block 32 is provided with an outwardly extending flange 32^a at its lower end which underlies the hub 31^a of the agitator and thus supports it in position. The upper end of the hub 31^a is provided with an internally threaded recess in which is mounted a cap member 33 adapted to close the upper end of the tub and prevent the exit of washing fluid to the upper end of the shaft 30. The hub 31^a of the agitator is formed integrally with a downwardly extending tube or sleeve 31^b which is spaced outwardly from the standard 22 and which is provided at its lower end with a relatively fixed bushing 34 having a bearing upon the external surface of the standard 22 so that when the shaft 30 is oscillated, the agitator has a firm support adjacent the upper and lower ends thereof. Between its upper and lower ends, the sleeve 31^b of the clothes agitator is formed integrally with a horizontally extending disk 31^c which is preferably pentagonal in form and which is provided around its margin with an outwardly extending rib 31^d. From the center of each of the five straight edges 31^e of this disk, there extends radially inward a rib or corrugation 31^f of inverted V-shaped cross-section which diminishes in magnitude toward the center of the agitator and disappears at or outwardly from the sleeve 31^b, as shown in Fig. 3. These ribs or corrugations 31^f thus provide upwardly extending radial projections on the upper side of the disk and corresponding recesses on the under side of the disk. From the apices of the pentagonal disk, there extend radially inward a plurality of hollow ribs 31^g which project downwardly from the bottom of the disk and are united at their inner ends with the tube or sleeve 31^b. These ribs are preferably enlarged in a vertical plane from the axis of the agitator outwardly so that their lower edges are downwardly and outwardly inclined and these lower edges terminate in upwardly curved surfaces 31^h which unite with the disk 31^c at the margin thereof. These ribs 31^g, being hollow, provide a series of corresponding recesses or depressions 31ⁱ in the upper face of the disk 31^c, each depression extending from the tube or sleeve 31^b to the junction of two of the edge surfaces

31^e of the disk. The agitator 31, thus formed, is adapted to have an oscillatory or reciprocatory motion about a vertical axis corresponding to the oscillatory motion of the shaft 30 and the washing fluid and clothes contained within the tub 20 are adapted to be violently agitated by this oscillatory motion. The upwardly extending ribs 31^f which taper downwardly and inwardly toward the center of the agitator act in conjunction with the depressions 31^e to effect a turbulent and irregular agitation of the washing fluid located above the disk of the agitator and the downwardly extending ribs or projections 31^g are adapted to effect a corresponding violent and irregular agitation of the washing fluid contained beneath the disk of the agitator. The pentagonal form of the disk is adapted to operate in conjunction with the effect of the ribs on the upper and lower sides thereof to produce the required agitation of the washing fluid and clothes located between the outer margin of the disk 31^c and the surrounding cylindrical wall of the tub which is preferably spaced outwardly from the disk to a sufficient extent to permit exit of the hands of the operator to the lower part of the tub. 5 10 15 20 25

The mechanism for imparting an oscillatory motion to the shaft 30 is contained within a housing 35 which is secured to the under side of the frame or housing 15 by cap screws 36. This housing 35 is provided beneath the center of 30 the tub with a recess 37 in which is located a ball bearing 38 having the lower end of the shaft 30 journaled therein. Above this bearing, the shaft 30 has secured thereon a pinion 39 which meshes with an oscillatory frame or rack 40 having an 35 arcuate series of rack teeth 40^a at the end thereof to mesh with the teeth of the pinion, as shown particularly in Fig. 9. At its opposite end, this frame or rack 40 is provided with a hub 40^b which is pivotally mounted upon a hollow sleeve or 40 bearing 41 carried by a bearing plate 42 which is capable of adjustment as hereinafter described for the purpose of moving the teeth of the rack 40 into and out of mesh with the pinion 39. The plate 42 rests upon the upper end of the hub or 45 sleeve 40^b and this sleeve in turn rests upon the upper face of a gear 43 which is splined upon the lower end of a vertical shaft 44 and which is provided with a downwardly extending cylindrical part 43^a journaled in a bearing hub 45 50 formed in the lower part of the housing 35. The shaft 44 extends vertically upward to a point above the upper end of the tub 20 and it is housed within a stationary tube 46 which is secured in a bearing block 47 formed as a part of the frame 55 15. When the gear 43 is rotated by the mechanism hereinafter described, the shaft 44 is operated to drive a clothes wringer or ironing machine which may be mounted in swinging position about the upper end of the tube 46 and supported 60 upon the bracket 48 which is carried by the upper part of this tube, as shown in Fig. 1. The plate 42 which carries the bearing sleeve 41 is pivotally connected by a pin 49 with the frame or housing 15 and is adapted to be swung about this pivot 65 for the purpose of varying the position of the sleeve 41 and thus moving the teeth of the rack 40 into or out of engagement with the pinion 39. This movement of the plate 42 may be effected by means of a crank pin 50 which is eccentrically 70 mounted on the lower face of a crank disk 51 formed on the lower end of a short vertical shaft 52 having a bearing in the bearing block 47. A crank handle 53 is secured upon the upper end of this shaft 52 and the crank pin 50 pivotally en- 75

gages a block 54 which is slideable in a groove 42^a formed in the plate 42, as shown in Fig. 10, so that when the shaft 52 is rotated by the crank handle 53, the block 54 is reciprocated in its groove to swing the plate 42 about the pin 49. A coil spring 55 is mounted between the block 54 and the inner end of the groove 42^a so that the block is normally forced in an outward direction from the pivot pin 49, thus tending to maintain the rack teeth in engagement with the teeth of the pinion 39.

The rack 40 and the gear 43 are both actuated by an electric motor 60 which is suspended from the frame 15 with its shaft 61 extending horizontally and connected by a coupling 62 with a worm 63 which is journaled at its ends in bearings 64 carried by one side of the housing 35, as shown in Figs. 2 and 9. The worm 63 meshes with a worm gear 65 which revolves about a shaft 20 66 secured in the frame 15 and the housing 35 as illustrated in Fig. 7. The shaft 66 extends through a slot in the rack member 40 which is located above the gear 65 and the hub of this gear extends upwardly and has an eccentric 68 formed integrally therewith. This eccentric rotates in a circular bearing 69^a formed in a block 69 which is mounted to slide in a guideway 40^c formed in the rack member 40, as illustrated in Fig. 8. The eccentric 68 is thus continuously rotated when the motor 60 is in operation and this causes an oscillation of the rack member 40 about the bearing sleeve 61 with a resulting oscillation of the agitator shaft 30 when the rack member is in engagement with the pinion 39. The gear 65 meshes with a small gear 70 which rotates on a stub shaft 71 secured in a plate 72 detachably secured to the under side of the housing 35 by means of studs 73, as shown in Fig. 7. The gear 70 is secured by a pin 74 to a pinion 75 which rotates upon the upper end of this stub shaft and this pinion meshes with the gear 43, previously described, to drive the vertical shaft 44. This mechanism for driving the shaft 66 and effecting an oscillatory motion of the agitator shaft 30 is not a part of the present invention but is described and claimed in my co-pending application Serial No. 338,456, filed February 8, 1929.

Although one form of the invention has been shown and described by way of illustration, it will be understood that it may be constructed in various other embodiments coming within the scope of the appended claims.

I claim:

1. The combination in a washing machine, of a tub for containing washing fluid, a shaft extending upwardly through the bottom of said tub, means for actuating said shaft, and an agitator mounted in fixed position on said shaft and comprising a horizontal disk spaced upwardly from the bottom of said tub to provide a clothes washing space beneath it, said disk being of polygonal

form and having radially extending vanes on the lower side thereof terminating at the apices of said disk.

2. The combination in a washing machine, of a tub for containing washing fluid, a shaft extending upwardly through the bottom of said tub, means for actuating said shaft, and an agitator mounted on said shaft above the bottom of said tub and comprising a horizontal disk of polygonal form having vanes extending inwardly from 10 apices thereof and other vanes on the other side of the disk extending inwardly at right angles to the sides of said disk.

3. The combination in a washing machine, of a tub for containing washing fluid, a shaft extending upwardly through the bottom of said tub, means for actuating said shaft, and an agitator mounted on said shaft with a washing space beneath it above the bottom of the tub and comprising a horizontal disk of polygonal form having upwardly projecting vanes extending inwardly at right angles to the sides of said disk and having other radially extending vanes on the lower side of the disk.

4. The combination in a washing machine, of a tub for containing washing fluid, a shaft extending upwardly through the bottom of said tub, and an agitator mounted on said shaft and comprising a polygonal disk spaced upwardly above the bottom of said tub to provide a clothes washing space beneath it, said agitator comprising two series of radially extending vanes each gradually increasing in depth gradually from the center of the agitator outwardly to its outer end, one series of vanes being located on the upper side 35 of said disk and the other series of said vanes being located on the lower side of said disk.

5. The combination in a washing machine, of a tub for containing washing fluid, a vertical shaft extending upwardly through the bottom of said tub, and an agitator mounted on said shaft and comprising a horizontal disk of polygonal form, said disk being provided on one side with a series of radially extending vertical vanes directed inwardly from the apices of said disk, said disk being provided on the other side with another series of radial vanes extending inwardly from the sides of said disk at points midway between said apices, the vanes of each series increasing in depth from the center of the agitator 50 outwardly.

6. The combination in a washing machine of an agitator comprising a central sleeve united integrally with an outwardly extending disk of polygonal form, said disk having hollow vanes extending downwardly from the lower side thereof with corresponding depressions on the upper side of said disk, said disk being further provided with radial corrugations forming upwardly extending radial vanes at points between said first named 60 vanes.

JOHN T. HUME.
